STILL CONSTRUCTION AND THE LIKE

Charles F. Pollen, Winnetka, Ill., assignor to M. H. Detrick Company, Chicago, Ill., a corporation of Delaware

Application July 15, 1935, Serial No. 31,303

18 Claims. (Cl. 122—356)

This invention relates generally to furnace construction, and pertains particularly to improvements in large stills of the kind employed for the cracking and distillation of petroleum. In such stills the oil is passed through banks of tubes which are exposed within a furnace chamber, for the purpose of subjecting the oil to the desired temperatures. Some of these tubes are arranged to receive radiant heat from the fire that is produced in the furnace chamber. Others are arranged more particularly for transfer of heat from the gaseous combustion products by convection. The furnaces or stills in which the heating fuel is burned and the tubes subjected to heat 5 are customarily built of or lined with bricks or tiles made of fire clay or other suitable refractory material.

A general object of the present invention is the provision of an improved construction for 10 the convection section of such stills.

A more particular object is the provision of a construction whereby the thickness and weight of the refractory wall or walls of the convection section may be very materially reduced, and at 15 the same time said walls maintained tight and in proper alignment both vertically and horizontally and in proper association with the tubes of the convection section.

Another object is the provision of an improved 20 construction for the convection section for oil stills which will have the advantages above indicated and which is quite simple in construction and may be built throughout of refractory tiles of but two different sizes or shapes.

Yet another object is the provision of improved 25 construction for the convection section of oil stills, which will facilitate the erection of the convection section refractory walls and the repair thereof, as well as the dismantling of the walls for inspection of or access to the convection tubes.

Other and further objects of the invention will 30 be pointed out or indicated hereinafter, or will be apparent to one skilled in the art upon employment of the invention in use.

For purpose of explaining the invention, I illustrate 35 in the accompanying drawings forming a part of this specification, and hereinafter describe, one form in which it may be embodied. It is to be understood, however, that this is presented merely for purpose of illustration, and is not to be construed in any fashion calculated to limit the appended claims short of the true and most comprehensive scope of the invention 40 in the art.

In said drawings,

Fig. 1 is a shortened part longitudinal sectional elevation of a still containing a convection section constructed in accordance with the invention;

Fig. 2 is a detail, on a larger scale, showing a transverse sectional elevation of a portion of the convection section wall and associated parts;

Fig. 3 is a part horizontal section through a portion of the convection section, same being 10 taken on approximately line 3—3 of Fig. 1;

Fig. 4 is an outer side elevational view of a portion of the convection section wall;

Fig. 5 is a detail, on a larger scale, of a portion of Fig. 3; and

Fig. 6 is a perspective view of a form of refractory tile which may be employed in the construction.

In said drawings, the reference numeral 10 designates the front wall of the furnace or still 20 chamber, 11 the roof of same, and 12 one of the side walls. As will be readily understood, there is a corresponding side wall opposite the wall 12, which walls customarily are about 28 feet apart, so that the internal width of the furnace chamber 25 is approximately 28 feet. The chamber is fired through its walls by means of a plurality of burners such as indicated at 14, the combustion of fuel taking place within and the heat and products of combustion being confined within 30 the chamber formed by the side walls, roof, end wall 10 and the corresponding end wall at the other extremity of the chamber.

Banks of tubes 15 are exposed within the furnace chamber, said tubes extending transversely 35 through it and through the side walls and being connected to appropriate headers, so that oil may be supplied to and passed through them. The tubes 15 are thus exposed to the fire in the furnace chamber, so that heat may be transferred to the oil which they contain.

The still is provided with one or more convection sections spaced longitudinally of the chamber from the burners 14. Where a convection section is located, the floor 16 of the furnace is 45 interrupted by a passage 17 which usually extends the full width of the chamber and forms an outlet for passage of combustion gases from the furnace chamber to a flue passage below the floor, which flue passage leads to the stack. 50 Over this outlet passage 17 are disposed banks of convection tubes 18, which convection tubes, like the tubes 15, extend across the furnace chamber and through the side walls and have suitable connection, as by headers and the like, for sup- 55

plying oil to them. At intervals transversely of the furnace chamber, tube sheets 19 are disposed in parallel upright relationship above the passage 17. Said tube sheets are made of suitable metal qualified to withstand high temperatures, and at their bottoms they have flanged foot portions 19a which rest on the furnace floor or foundation. They are provided with apertures which accommodate the tubes 18, and which 10 serve as supports for said tubes. Their vertical margins may be provided with laterally extending flanges 19b (see Fig. 5).

Along the sides of the convection tube banks and the passage 17 are disposed the convection section walls, which are indicated generally by the reference numeral 20. These walls extend entirely across the furnace chamber, from one of its side walls to the other. These walls may be built up for the most part of refractory tiles of the form shown in Fig. 6 and designated elsewhere on the drawings by the reference numeral 21, together with baffle tiles 22. These tiles preferably are of relatively small size in their dimensions of width and thickness, e. g., five and one-half inches by three inches. Their broader side faces are each provided with a series of projections 21a interspaced by seats 21b, a series of projections 21c interspaced by seats 21d, and a series of short marginal projections 21e interspaced by seats 21f, the projections on one side being opposite corresponding seats on the opposite side. Their narrower side faces are provided each with a series of projections 21g interspaced by seats 21h, the projections on one of said faces being opposite the seats on the other. These projections and seats extend parallel to the end faces of the tile, and they occupy something over one-half the total length of the tile. At a suitable distance from one end, the narrower side faces are grooved across as shown at M and N, to form shoulders 21j and 21k, said shoulders being of approximately the same width, but the shoulder 21k being inset from its side of the tile, whereas the shoulder 21j is approximately flush with its side of the tile.

The baffle tiles 22 are similarly formed with projections and seats, but they are not provided with the notches and shoulders, and are somewhat longer than the tiles 21.

50 The walls 20 are built up of courses of the tiles 21 and 22 laid as illustrated in Figs. 2 and 4, the projections 21h and seats 21g of tiles in the same course being intermeshed and the other seats and projections of the tiles in adjacent courses being 55 intermeshed. Course by course, the tiles are inverted, viz., in the first course the tiles are laid with their shoulders 21j to the right, the tiles of the second course are laid with their shoulders 21k to the right, the tiles in the third course are 60 laid with their shoulders 21j to the right, and so on, the shoulders of the superimposed tiles all being in alignment vertically. Consequently, the vertical joints between the tiles of one course are staggered or offset with respect to the vertical 65 joints between the tiles in the courses subjacent and superjacent thereto. Accordingly, each tile is intermeshed with two tiles in the subjacent course and two tiles in the superjacent course.

Because of the intermeshing of the projections 70 and seats of the tiles, all of the joints through the wall are tortuous. The projections are somewhat narrower than the seats, and to fill the resulting voids the tiles are dipped with a thin slurry of fire clay before they are laid up. This 75 filling material is friable when dry and accord-

ingly the tiles are afforded a slight degree of movement relative to one another without imposing breaking pressures on their projections, the filling material being held by the projections and seats against sifting out, and hence being always 5 effective to seal the joints between the tiles.

The baffle tiles 22 are used to form the courses which are opposite the in-set sides of the tube banks, their elongated ends projecting into proximity with the in-set tubes, as illustrated in Figs. 10 1 and 2, to prevent the hot gases traveling directly downward along the wall. The elongated end portions of the tiles 22 are cut, where necessary, to accommodate the tube sheets 19 and the flanges 19b thereof.

15 The walls 20, assembled as above described, are erected along the sides of the tube banks in parallel relationship thereto and along the margins of the tube sheets. The flanged vertical margins 19b of the tube sheets may contact the proximate 20 ends of some of the wall tiles, as illustrated in Figs. 3 and 5. In the course of the erection of the walls, rods 24 are inserted between the tube banks at appropriate horizontal and vertical intervals, said rods carrying anchor members 25 at 25 their ends. The rods 24 rest on the tubes, and the anchor members 25 are accommodated between the shoulders of juxtaposed tiles 21 and have laterally projecting flanges 25a which engage behind the shoulders of the juxtaposed tiles, 30 as seen in Fig. 5. The arrangement permits the anchoring means to shift vertically with respect to the tiles, the tubes, and the tube sheets. The rods and anchor members thus serve to anchor the walls in parallel association with each other 35 and the tube banks, and, if desired, hold some of the tiles against the margins of the tube sheets 19. This is accomplished without imposing the weight of the tubes on the tiles or the weight of the tiles on the tubes and without subjecting the 40 anchoring members to strains incident to vertical expansion of the wall. The rods and anchor members are formed of appropriate metal having the qualities requisite to withstand high temperatures.

45 Accordingly, it will be seen that the walls 20 are maintained in proper association with the tubes 18 throughout the entire horizontal and vertical extent of said walls by virtue of the fact that the wall tiles are intermeshed with one another both horizontally and vertically and the courses interlocked longitudinally of the wall, the tube sheets acting as spacers for the walls and preventing abutment of the walls against the tubes. It will be appreciated that if the convection section is adjacent the end wall opposite that in which the burners are positioned, a similar construction may be employed, the end wall of the furnace serving also as one of the convection section walls.

60 In the operation of the still, the fuel fed by the burners is burned in suspension in the furnace chamber, the tubes 15 being subjected to the radiant heat of the flames and the heat of the burning gases. The burned hot gases enter 65 at the top of the convection section and pass downwardly between the walls 20, heat being transferred from the gases to the tubes 18 and the contents thereof, and the gases pass out through the passage 17 into the flue conduit 70 below the furnace floor.

65 The construction above described provides a comparatively thin yet at the same time very tight wall for the convection section. In the constructions heretofore employed, it has been 75

necessary to build the convection section walls quite thick in order to prevent leakage through them and to hold their shape under thermal expansion. The convection section walls are subjected to the furnace heat on both sides, although the temperature on the sides toward the convection tubes will be considerably lower than that on the outer sides. Inasmuch as in my construction each tile extends through the entire thickness of the wall and each is exposed to heat at both its ends, there will not be as great a heat differential through a tile as there would be in the thicker wall constructions in which the respective tiles are exposed to the furnace heat on only one end. Accordingly, my construction avoids distortion of the wall from thermal expansion and reduces the likelihood of fracture of the tiles from strains resulting from unequal expansion of the wall and large temperature differentials in respective tiles. By use of my construction, moreover, a very considerable amount of space in the furnace chamber is saved for combustion, particularly in installations which contain two or three convection sections. Accordingly, the furnaces may be made materially shorter without reduction of combustion space.

Furthermore, substantial savings in material and cost of construction are effected as compared with former installations, not only in the wall itself, but also in the foundations for the wall, and dismantling of the wall for repair or for access to the tubes is greatly facilitated.

What I claim is:

1. In still construction and the like, the combination with upright tube sheets for positioning the still tubes, of refractory walls extending along the margins of the tube sheets and built up of refractories having intermeshing engagement with one another, and anchor means engaging end portions of some of the refractories in the opposite walls and holding the walls in engagement with the vertical margins of the tube sheets.

2. In still construction and the like, the combination with upright tube sheets for positioning the still tubes and arranged at intervals and in alignment with one another, of refractory walls extending along the vertical margins of the tube sheets and built up of tiles which have projections and seats extending transversely of their faces, the projections and seats of the juxtaposed tiles being in intermeshing relationship and anchor means engaging end portions of some of the tiles in the opposite walls and anchoring the walls in engagement with the vertical margins of the tube sheets.

3. A construction as specified in claim 1 and wherein at least one of the walls is in the nature of a bridge wall within the still chamber and each of its tiles has an end exposed at each side of said wall.

4. A construction as specified in claim 2 and in which the tiles in some of the wall courses are longer than those in others and project between the tube sheets.

5. In still construction and the like, the combination with upright tube sheets arranged at intervals and in alignment with one another for positioning the still tubes, refractory walls extending along the vertical margins of the tube sheets and built up of refractory tiles having their contacting sides formed with projections and seats in intermeshing relationship so that the joints between the tiles are of tortuous form through the major portions of the walls' thickness, and anchoring means engaging end por-

tions of some of the tiles in the opposite walls and holding the walls in engagement with the vertical margins of the tube sheets.

6. A construction as specified in claim 5 and in which the tiles in some of the wall courses project between the tube sheets.

7. A construction as specified in claim 1 and in which the anchoring means are movable relative to the tubes and tube sheets.

8. In still construction, the combination with upright tube supports arranged at intervals and in alignment with one another for supporting the still tubes in approximately horizontal position, of a refractory wall extending along upright margins of the tube supports and built up of tiles arranged in courses, the adjacent tiles having portions in intermeshing relationship with one another, some of the tiles having shoulders at their ends adjacent the tubes, and anchoring members engaging shoulders of some of the tiles, and means holding said anchoring members against movement transversely of the tubes, to retain the wall in association with the tube supports, the tiles being shiftable vertically relative to the anchoring members to accommodate expansion.

9. A construction as specified in claim 8 and wherein the wall is within the still chamber and each of its component tiles extends entirely through the wall and has an end surface exposed at each side of the wall.

10. A construction as specified in claim 8 and in which the wall is within the still chamber and each tile extends entirely through the wall and has an end surface exposed at each side thereof, the tiles in some of the courses being longer than those in others and extending between the tube supports.

11. A construction as specified in claim 1 and wherein the tiles are arranged in courses and each tile has intermeshing engagement with two tiles in the subjacent course and with two tiles in the superjacent course.

12. A construction as specified in claim 8 and in which each tile has intermeshing engagement with two tiles in the subjacent course and with two tiles in the superjacent course.

13. In still construction and the like, the combination with a bank of horizontally extending tubes and means for supporting them, of refractory walls extending along opposite sides of said tube supporting means, said walls being built up of tiles arranged in courses, and anchor members supported on the tubes in horizontal and vertical spaced relationship to each other and inter-engaged with end portions of tiles in the opposite walls to retain the walls in parallel relationship and in engagement with the tube supporting means.

14. A construction as specified in claim 13 and wherein the tiles in the respective walls are arranged in intermeshing relationship and the anchor means is shiftable vertically relative to the tubes.

15. A construction as specified in claim 13 and wherein the tiles in the respective walls are arranged in intermeshing relationship and each tile is exposed at both sides of the wall.

16. In still construction and the like, the combination with upright tube supports arranged in a row at intervals, of refractory walls extending along the opposite upright margins of the tube supports and built up of refractory tiles having projections and seats arranged in intermeshing

relationship, and anchoring members spaced from each other longitudinally and vertically of said walls and inter-engaged with end portions of tiles in the opposite walls to retain the walls against displacement outwardly from engagement with the upright margins of the tube supports.

17. A construction as specified in claim 8 and wherein the anchoring means are arranged at intervals longitudinally and vertically of the wall

and are shiftable longitudinally of the tubes and vertically relative to the tube supports.

18. A construction as specified in claim 16 and wherein the anchoring means are arranged at intervals longitudinally and vertically of the walls and are shiftable relative to the tube supports and tiles. 5

CHARLES F. POLLEN.
